UNITED STATES PATENT OFFICE.

HERMAN K. VOSBURGH, OF WEST HARTFORD, CONNECTICUT.

DESIGN FOR A BAKE-PAN.

SPECIFICATION forming part of Design No. 25,482, dated May 12, 1896.

Application filed March 26, 1896. Serial No. 585,016. Term of patent 7 years.

To all whom it may concern:

Be it known that I, HERMAN K. VOSBURGH, a citizen of the United States of America, residing at West Hartford, in the county of 5 Hartford and State of Connecticut, have invented and produced a new and original Design for Bake-Pans, of which the following is a specification, reference being had to the accompanying drawings, wherein—

10 Figure 1 is a side view. Fig. 2 is an end view.

The design comprehends a bake-pan closed on all sides and ends, necessarily made in

parts, which allow it to be opened. It is shown in the drawings as having a median 15 horizontal line along the center along the line *a*. It is many-sided—hexagonal—and it is this which constitutes the leading feature of the design.

I claim as my improvement—

20 The design for a bake-pan substantially as shown and described.

HERMAN K. VOSBURGH.
